UNITED STATES PATENT OFFICE.

GEORGE C. MARTEN, OF EFFINGHAM, ILLINOIS.

COMBINATION-TOOL.

1,374,751.

Specification of Letters Patent.

Patented Apr. 12, 1921.

Application filed April 12, 1919. Serial No. 289,650.

To all whom it may concern:

Be it known that I, GEORGE C. MARTEN, a citizen of the United States, residing at Effingham, in the county of Effingham and State of Illinois, have invented certain new and useful Improvements in Combination-Tools; and I do hereby declare the following to be a full, clear, and exact description of the invention, such as will enable others skilled in the art to which it appertains to make and use the same.

My invention relates to improvements in breast drills having means to adapt itself to the grinding of valves and so forth.

An important object of this invention is to provide a breast drill having means to adapt itself for grinding valves so that the valve is caused to rotate in opposite directions, the angular movement of the valve in one direction being greater than in the other direction.

A further object of the invention is to provide a drill of the character described which by virtue of its extreme simplicity and reliability in use will meet with commercial favor when placed upon the market.

Other objects and advantages of this invention will be apparent during the course of the following description.

In the accompanying drawings forming a part of this specification, and in which like numerals are employed to designate like parts throughout the same.

Figure 1 is a vertical section through the tool embodying my invention.

Fig. 2 is a vertical section through the same taken at right angles to the plane of Fig. 1.

Fig. 3 is a vertical section taken on line 40 3-3 of Fig. 2.

Fig. 4 is a section through an auxiliary power transmitting mechanism adapted for use when it is desired to gain access to valves located in difficult places, and

Fig. 5 is an elevation of one of the gear wheels embodied in the invention.

In the drawings wherein for the purpose of illustration is shown the preferred embodiment of my invention, the numeral 10 designates the frame of a breast drill having the usual handle or breast piece 11 secured thereto by a set screw 12. The frame 10 carries a yoke 13 receiving a pinion 14 upon a vertical shaft 15. The shaft 15 is connected with the usual chuck 16. The frame 10 is provided with a transversely ex-

tending opening 17, which, when the tool is to be employed as a drill, affords a bearing for a shaft 18. The shaft 18 is provided with a gear 19 having a circular series 60 of gear teeth 20 adjacent its center and meshing with the pinion 14. The gear 19 is held in engagement with the shaft 18 by a set screw 21. A handle 22 may also be arranged on the shaft 18 and secured thereto 65 by a set screw 22'. When the shaft 18 is journaled in the bearing openings 17 the drill is adapted for use as an ordinary breast drill and imparts a continuous rotary movement to the chuck when the crank 70 handle is turned.

As illustrated in Figs. 1 and 2, the drill is adapted for use in grinding valves. A second gear 23 coöperates with the gear 19 and is mounted on the shaft 18. To permit 75 of the ready removal of the gear 23 from the shaft 18, I have provided a spring latch 24 having its ends 25 extending into recesses in the outer side of the gear 23. The spring is formed intermediate of its ends 80 with a convolution providing a latch finger 26 adapted to be sprung into recesses 27 formed in the squared end portion 28 of the shaft 18 and the hub portion of the gear thereby locking the gear to the shaft 85 and yet permitting of its ready removal. The gear 23 is provided with spaced sets 90 of teeth 29 adapted to engage the pinion 13 periodically. The coöperating gear 19 is also provided with spaced sets of teeth 30 alternately disposed with relation to the spaced sets of teeth of the gear 23.

The sets of teeth 29 and 30 are adapted to alternately engage the pinion 13 and thereby rotate the chuck in opposite directions. 95 The teeth of each set 30 are greater in number than the teeth of each set 29 and therefore the chuck is caused to rotate a greater number of times in one direction than in the other. To engage the teeth 29 and 30 with the pinion 13, I have provided an opening 31 disposed above the opening 17 and adapted to receive the shaft 18. The chuck 16 is adapted to receive a valve engaging element 32 having the usual fingers 33.

With reference to the foregoing construction it will be apparent that the ordinary breast drill constructed in accordance with my invention may be readily converted into a valve grinding device.

The auxiliary power transmitting device illustrated in Fig. 3 includes a bearing sleeve

34 having a second bearing sleeve 35 connected thereto by a web 36. The bearing sleeve 34 receives a shaft 35' having its rear end squared to fit into the chuck 16. The 5 forward end of the shaft 35' carries a bevelled gear 36^a meshing with a second bevel gear 37. The bevel gear 37 is keyed to a vertical shaft 38 rotatively mounted within the bearing sleeve 35. This form of the invention is especially adapted for use when 10 it is desired to arrange the breast drill in a horizontal position when grinding the valves. The forward end of the shaft 38 is provided with a socket 39 having a set screw 15 40. The socket 39 receives a valve grinding element 41 which consists of a stem having a universal joint 42 interposed therein. The forward end of the valve grinding element 41 is provided with fingers 43 adapted to 20 engage the valve.

While I have shown and described the preferred embodiment of my invention, it is understood that I may make such minor changes in arrangement and construction of parts as will remain within the spirit of the invention and the scope of the appended claims.

Having thus described my invention, what I claim is:—

30 1. In a device of the class described, a frame having spaced bearings, a shaft journaled for rotation in the frame, a pinion upon the shaft, an operating shaft adapted to be journaled in the first mentioned bearings, interchangeably, means whereby the last mentioned shaft may be rotated, a gear fixed upon the last mentioned shaft at one side of the same and having concentric series of gear teeth, one series having its teeth arranged in spaced sets and adapted to mesh with the pinion when the shaft is mounted in one of the bearings, and the other series adapted to mesh with the pinion when the shaft is mounted in the other bearing, and
35 40 45 a gear removably mounted upon the operat-

ing shaft at the other side of the same and having a series of gear teeth arranged in spaced sets and adapted to mesh with the pinion alternately with the sets of the first mentioned series of the first mentioned gear when the operating shaft is mounted as first stated, the last mentioned gear constituting also means for preventing longitudinal displacement of the operating shaft in the bearing. 50

2. In a device of the class described, a frame having spaced bearings, a shaft journaled for rotation in the frame, a pinion upon the shaft, an operating shaft adapted to be journaled in the first mentioned bearings, interchangeably, means whereby the operating shaft may be rotated, a gear fixed upon the operating shaft at one side of the frame and concentric series of gear teeth, one series having its teeth arranged in spaced sets and adapted to mesh with the pinion when the shaft is mounted in one of the bearings and the other series adapted to mesh with the pinion when the shaft is mounted in the other bearing, the shaft in its end at the opposite side of the frame having a socket, a gear removably mounted upon the last mentioned end of the shaft at the said opposite side of the frame and having a series of gear teeth arranged in spaced sets and adapted to mesh with the pinion alternately with the sets of the first mentioned series of the first mentioned gear when the operating shaft is mounted as first stated, and a latch carried by the last mentioned gear and having a portion engageable in the socket whereby to separably connect said last mentioned gear with the said operating shaft.

In testimony whereof I affix my signature 85 in presence of two witnesses.

GEORGE C. MARTEN.
